UNITED STATES PATENT OFFICE.

JOHN BRADFORD, JR., OF WINSLOW, ILLINOIS.

THILL-COUPING.

SPECIFICATION forming part of Letters Patent No. 476,443, dated June 7, 1892.

Application filed October 10, 1891. Serial No. 408,347. (No model.)

To all whom it may concern:

Be it known that I, JOHN BRADFORD, Jr., a citizen of the United States of America, residing at Winslow, in the county of Stephenson 5 and State of Illinois, have invented certain new and useful Improvements in Thill-Couplers, of which the following is a specification.

My invention relates to improvements in thill-couplers, and is fully described and explained in this specification and shown in the accompanying drawings, in which—

Figure 1 is a side elevation of my improved thill-coupler in operative position upon an axle. Fig. 2 is a longitudinal vertical section 15 thereof, and Fig. 3 is a top plan of the same.

In the views, A is an axle of ordinary form, B the clip encircling the same, and C the plate lying beneath axle and receiving the ends of the clip, which are secured by suitable nuts in the ordinary manner. The plate 20 C has a horizontal extension C' lying in front of the axle, and this extension terminates in two rearwardly-open hooks C², separated by a space of sufficient width to receive a thill-iron D, adapted to be fastened to a thill in the usual way. Upon the end of this thill-iron is integrally formed a transverse pin D', of such length and diameter as to engage both the hooks C² and receive the strain brought 25 upon the thills as the vehicle to which they belong is drawn forward. The pin D' is held in place by means of a swinging button E, held in place by a bolt made up of two parts F F', Fig. 2, preferably of different diameters, 30 the upper and slenderer part of the bolt being seated in the button and the lower and heavier portion being seated in a slot s in the extension C' of the plate C for the purpose of fastening the button adjustably on the plate.

Between the two parts F F' of the bolt is a head H, of greater diameter than the width of the slot. This head rests upon the upper surface of the plate, and nuts N N' engage the lower end of the bolt and fasten it securely 35 in any desired position, the plate being clamped between the nut N and the head H. On the upper end of the part F' of the bolt is a nut N², holding the button E in place and preventing its accidental escape. By means 40 of the head H any desired clamping force may be brought upon the plate extension C' for the purpose of holding the pivot securely in

place without unduly clamping the button, and the latter is thereby enabled to turn freely upon its pivot, no matter how firmly the nuts 55 N N' may be set against the lower face of the plate.

Upon the button E is a spring S, fastened at its rear end to the button by means of screws, the position and shape of the spring 60 being such that its free front end lies between the points of the two hooks C² C² and extends substantially across the space which separates them. The free end of the spring is turned up, as shown in Figs. 1 and 2, in such 65 a way that when in its normal position it prevents the swinging of the button in either direction; but the end of the spring may be easily pushed downward until it comes below the ends of the hooks, when the button may 70 be readily swung to the position shown in dotted lines in Fig. 3, thereby permitting the disengagement of the pin D' from the hooks and the detachment of the thill from the axle and its attachments. 75

The operation of this device, which is sufficiently evident from the drawings and the description, may be briefly stated as follows: When the thill is separate from the vehicle, the button being swung into the position 80 shown in dotted lines in Fig. 2, the pin D' is inserted in the hooks and drawn forward until it is pressed closely against them, and the button is then swung to the position shown in full lines in Fig. 3. As the button passes under the hook on the side from which it is moved the free end of the spring S is pressed downward; but as soon as the button reaches the position shown in Fig. 3 the end of the spring flies up to its normal position and locks 90 the button in place, thereby securing the button against accidental turning and the thill against accidental detachment. The thill may be removed by reversing this process in a manner which is perfectly evident. 95

Having now described and explained my invention, what I claim as new, and desire to secure by Letters Patent, is—

1. In a thill-coupler, the combination, with an axle-clip and a plate fastened thereto and provided at its front end with rearwardly-open hooks separated by a suitable space, of a thill-iron provided at its rear end with a transverse pin adapted to engage said hooks, a lat-

erally-swinging button pivoted to the plate and adapted to lock the pin in place, and a spring fastened to the button and adapted when the button is in working position to lie 5 between the hooks of the plate and prevent accidental rotation of the button, but to be pressed downward and passed under the point of one of said hooks as the button is swung out of working position, substantially as 10 shown and described.

2. The combination, with the plate C C', provided with the hooks C², of the thill-iron D, having the transverse pin D', adapted to engage said hooks, the laterally-swinging button E, pivoted to the plate and adapted to lock the pin in place, and the spring S, fastened to the button and having a free upturned end adapted to lie between said hooks, and prevent accidental rotation of the button or 15 to be pressed downward and passed under the point of one of said hooks, substantially as 20 shown and described.

3. The combination, with the plate provided with hooks C², of the thill-iron D, having the pin D', the button E, and the bolt 25 made up of two parts F F', separated by a head H, the part of the bolt below the head being passed through the plate and both ends of the bolt being provided with nuts for the purpose, respectively, of locking the bolt to 30 the plate and locking the button to the bolt, substantially as shown and described.

4. The combination, with the plate C C', provided with hooks C² and having a slot s, of the thill-iron D, having the pin D', the button E, pivoted to the plate by a bolt passing through and adjustable in the slot s, and the nuts N N' N², securing the bolt in the slot and securing the button upon the bolt, substantially as shown and described.
